(57) **CLAIM**

The ornamental design for a remote control cover, as shown and described.

DESCRIPTION

FIG. 1 is a top plan view of a remote control cover showing my new design;

FIG. 2 is a right side view thereof; and,

FIG. 3 is a top perspective view in use.

The broken line showing of the remote control in FIG. 3 depicts environmental structure and forms no part of the claimed design.

1 Claim, 2 Drawing Sheets(56)
